UNITED STATES PATENT OFFICE.

JOSEPH MITCHELL PAYNE, OF CRESSONA, PENNSYLVANIA.

ELECTRIC BRAKE.

SPECIFICATION forming part of Letters Patent No. 451,514, dated May 5, 1891.

Application filed March 31, 1890. Serial No. 346,066. (No model.)

To all whom it may concern:

Be it known that I, JOSEPH MITCHELL PAYNE, a citizen of the United States, residing at Cressona, in the county of Schuylkill 5 and State of Pennsylvania, have invented a new and useful Improvement in Electric-Brake Apparatus, of which the following is a specification.

My invention relates to an improvement in 10 electric-brake apparatus for railway-cars and in couplings for the same; and it consists in the peculiar construction and combination of devices that will be more fully set forth hereinafter, and particularly pointed out in the 15 claims.

In the accompanying drawings, Figure 1 is an elevation of a railway-car provided with coupling devices and an electric brake embodying my improvements and showing the 20 manner of coupling the cars together. Fig. 2 is a bottom plan view of the same. Fig. 3 is an end elevation of the car. Fig. 4 is a detail perspective view of the coupling. Fig. 5 is a sectional view of the same, showing the 25 draw-heads coupled together. Fig. 6 is a sectional view taken on the line $x-x$ of Fig. 5.

A represents the draw-heads, which are pivoted to draw-bars B, that are secured under the ends of the car C in the usual manner 30 and are provided with the usual buffer-springs D, the draw-bars being movable longitudinally under the car. Each draw-bar is provided on opposite sides with ears E. Each draw-head is provided with a pair of rearward- 35 extending oppositely-inclined shoulders F, arranged substantially in the form of an arrow-head. The said shoulders F of one draw-head are provided with rearward-extending pins G, and the shoulders of the companion 40 draw-head have openings H to receive the pins, the inner sides of said openings being flared outwardly, as shown in Fig. 6, to permit the pins G to work loosely therein when 45 the cars are coupled together, thus rendering the coupling flexible and enabling the cars to readily pass around curves.

A lever I is pivoted on each end of each car and connected to one of the draw-heads by a chain or link K, each of the said levers 50 engaging a detent or ratchet-plate L, and thereby enabling the draw-head to be supported at any desired elevation, and the func-

tion of the levers being, also, to lower the draw-heads in the act of uncoupling.

M represents rock-shafts journaled in the 55 trucks of each car, midway between the axles thereof, said rock-shafts having upward-extending arms N.

O represents the brake-shoes, which are pivoted in the truck at their upper ends and are 60 adapted to engage the car-wheels. The said brake-shoes are connected to the rock-shafts M by links P. Attached to each arm N is a rod R, which is guided horizontally under the car by supports or brackets S, and has at its 65 inner end an armature T.

Secured under the bottom of the car are electro-magnets U, having their poles presented toward the said armatures, but out of contact therewith. In one of the cars, or in 70 the tender of the locomotive, is an electric battery V, having its terminals connected in series with the electro-magnets U throughout the entire length of the train, the couplings between the conductors W of said battery 75 and electro-magnets being effected between the cars by arrow-head-shaped electrodes X and electrodes Y, having clamps Z to engage the same. The said coupling devices are secured in transverse openings in the ears E of 80 the draw-bars, as shown in Figs. 1, 2, and 4. Included in the conductors W is a circuit-closer A', which is normally open, as shown in Fig. 2.

In order to apply the brakes it is only necessary to close this circuit-closer, and thereby cause the current of electricity to excite the electro-magnets U, when the armatures T will be attracted by the said magnets and cause the rods R to be moved lengthwise and partly 90 rotate the rock-shafts M and cause the links P thereof to apply the brake-shoes to the wheels, as will be very readily understood.

Having thus described my invention, I 95 claim—

1. The draw-bars provided with laterally-extending ears provided with perforations, in combination with the electrodes X Y, supported in said perforations, substantially as set forth.

2. The combination of the brake apparatus having the armatures, the electro-magnets to attract the armatures, the battery, the circuit-closer, the conductors connecting the bat-

tery and the electro-magnets, and the electrodes X Y, attached to the said conductors and supported in perforated lugs extending laterally from the draw-bars of the car, said 5 electrodes having the spring-clamps Z to connect them together between the cars, substantially as described.

In testimony that I claim the foregoing as my own I have hereto affixed my signature in presence of two witnesses.

JOSEPH MITCHELL PAYNE.
